UNITED STATES PATENT OFFICE.

WALLACE B. HUGHES, OF DALLAS, TEXAS.

FENCE-POST.

943,550.

Specification of Letters Patent. Patented Dec. 14, 1909.

Application filed April 16, 1909. Serial No. 490,417.

To all whom it may concern:

Be it known that I, WALLACE B. HUGHES, a citizen of the United States, residing at Dallas, in the county of Dallas and State of Texas, have invented new and useful Improvements in Fence-Posts, of which the following is a specification.

This invention relates to new and useful improvements in fence posts and it has more 10 particular reference to a fence post constructed of wire fabric.

The present fence post is intended as a substitute for wooden fence posts in those parts of the country where timber is scarce 15 and also as a substitute for concrete fence posts, which latter are not only more or less intrinsically expensive but are rendered further so by reason of high freight charges for transportation for any material distance.

The object of the invention is to provide a fence post which shall be a self-contained unit and which may be manufactured at a minimum expense. Toward this end the 25 structure comprises more particularly a fence post which is made up of wire fence fabric of known form and the resultant product is inexpensive, light and strong.

The invention aims as a further object to 30 provide a fence post of the type stated which may be used in connection with a wire fence of any desired gage and in which no special parts are necessary to provide for the attachment of the fence fabric to the 35 post, one of the strands of the fence fabric resting upon the projecting portion of a horizontal band of the post and a key being provided to lock the post and the fabric together.

40 In the drawings: Figure 1 is a perspective view of a fence post constructed in accordance with the present invention. Fig. 2 is a side elevation thereof, and Fig. 3 is a horizontal sectional view thereof.

45 Similar characters of reference designate corresponding parts throughout the several views.

The present fence post may be advantageously constructed of wire fence fabric of 50 known construction and which comprises vertical stay bars, as 5, and horizontal bars, as 6. The bars 6 in the construction of the present fence post are bent into the form of continuous bands which are preferably 55 of triangular outline and the bars 5 are attached to the side portions of the bands 6

in any suitable manner, as by welding. The contiguous ends of the bands 6 are likewise welded together. For the purpose of making a finished joint, the bars 5 at 60 their upper and lower ends are provided with eyes, as 7, through which the upper and lower bands 6 pass, a rigid connection being had by welding the parts together. Each band 6, by virtue of its straight sided 65 form, has a plurality of apices, as 8, which project through the spaces between a pair of adjacent bars 5, as clearly shown in Fig. 3. The several series of apices 8 are in vertical alinement and form in effect loops. 70 The fence fabric is indicated generally by the numeral 10 and includes horizontal wires, as 11, which are connected by vertical stay wires, as 12.

In assembling the fence fabric upon the 75 posts, the wires 11 are positioned against a pair of adjacent bars 5 on each side of a series of alined loops 8, the latter projecting beyond the fence fabric, as shown in Figs. 2 and 3. Obviously, irrespective of the gage 80 of the fence fabric, one of the wires 11 will rest upon one of the loops 8 and in this manner the fence fabric will be suspended from the post. In Fig. 2 the upper wire 11 is shown as resting upon a second loop 8. 85 When the fence fabric has been thus positioned with relation to the post, it is positively secured by a key, as 13, which is in the nature of a straight wire shank and which is inserted through the several alined 90 loops 8 and over the wires 11. The fence is thereby retained against displacement from the post. The key 13 is formed at its upper end with an eye, as 14, which is engaged over the loop 8 of the upper band 6 95 in such manner that accidental displacement of the key is rendered impossible and in order to remove the same the use of tools will be necessary.

The lower portion of the fence post may 100 be set into a suitable base which may be of any desired material, as for example, concrete or wood. This may be done at the place where the fence is being installed and it is not essential that the base be shipped 105 with the post. Or, if desired, the lower portion of the fence post is of sufficient strength to constitute of itself an efficient base and may be set directly into the ground without the use of wood, cement or other reinforcing 110 material.

It will be obvious that the present post has

many advantages over the solid posts ordinarily employed. In the first place, it is exceedingly light and consequently it may be cheaply transported by freight. In the 5 second place, it is very strong and offers practically no resistance to the wind. It is, therefore, not liable to be blown down or otherwise moved during heavy storms. In the third place, it may be manufactured at a 10 minimum expense for two reasons, the first being that it is made from fence fabric of known and inexpensive construction and the second being that no special loops or fastening devices are required for the attachment 15 of the post to the fence, the apices 8 in their particular relation to the adjacent bars 5 serving efficiently for this purpose and being employed in coöperation with a retaining key which comprises simply a straight 20 section of wire.

I am aware that it is well known in the art of fence construction to secure fence fabric to a post by means of loops on the post which project through the fabric and 25 which receive a retaining key. In such cases, however, the loops are of special formation and project at one side only from the corner of the post. In the present device the fence fabric may be secured to any 30 desired series of loops and thus renders the post of particular advantage for use at corners where one fence extends at an angle to another, it being understood that one fence is secured to one series of loops 8 and that 35 the other fence is secured to an adjacent series of loops 8.

For convenience and clearness of illustra-

tion, the fence has been shown of such gage that only one of its horizontal strands is supported upon a projecting loop of the 40 post. Obviously and preferably, the gage of the fence and of the post may be nearly the same in order that some of the strands of the fence may have support upon the corresponding loops of the post while the balance of the strands of the fence engage directly under the corresponding loops of the post. This insures rigidity, providing for the greatest resistance against any weight from the top and also preventing the fence 50 from being raised from the ground.

Having fully described my invention, I claim:

A fence post constructed of wire fabric comprising horizontal wires and vertical 55 stay wires, the horizontal wires being bent into the form of continuous uninterrupted bands, each having its adjacent ends secured together, said bands having straight sided portions and curved apices, the stay wires 60 intersecting the straight sided portions and being secured thereto, the apices being without stay wires and being arranged in vertically aligned series and projecting in the form of loops through the spaces between 65 the adjacent stay wires on each side thereof.

In testimony whereof I have hereunto set my hand in presence of two subscribing witnesses.

WALLACE B. HUGHES.
